UNITED STATES PATENT OFFICE

2,477,780

METHOD OF MAKING FINDINGS FOR EAR ORNAMENTS

George A. Armstrong, Barrington, R. I., assignor, by mesne assignments, to Budlong, Docherty & Armstrong, Incorporated, Providence, R. I., a corporation of Rhode Island

Application August 24, 1945, Serial No. 612,409

2 Claims. (Cl. 29—160.6)

1

This invention relates to an ear ornament and the method of making the same, or more particularly to the finding for an ear ornament.

In the making of ear ornaments it is usual to provide from tubular stock a short section which is internally threaded for the reception of the binding screw. This section is then soldered to a U-shaped portion of the ear wire as a separate assembly operation. Soldering is an expensive operation and one which requires considerable skill.

One of the objects of this invention is to provide the U-shaped portion of the ear wire and the threaded portion which receives the binding screw without the necessity of soldering.

Another object of this invention is to provide the U-shaped body portion and the portion which receives the binding screw piece so that soldering will be unnecessary and the parts will be strong and without joint.

Another object of this invention is to eliminate certain assembly operations.

Another object of this invention is to eliminate the necessity of cutting plated stock to provide the portion which receives the binding screw thus enabling the plating of the stock to cover all edges.

Another object of this invention is to provide an ear wire by such a method that no raw edges which come from cutting the stock will be provided, thus enabling the ear wire to be formed from plated stock with all parts or edges covered with the plate which goes to form the stock.

With these and other objects in view, the invention consists of certain novel features of construction, as will be more fully described and particularly pointed out in the appended claims.

In the accompanying drawings:

Fig. 1 is an elevation illustrating the finished article which is made by the method of this invention;

Fig. 2 is a perspective view illustrating a U-shaped length of wire prior to any operations except that of bending being performed thereon;

Fig. 3 is a perspective view showing the end of the wire as flattened;

Fig. 4 is a perspective view showing the flattened end as partially bent into cylindrical shape;

Fig. 5 is a perspective view of the flattened portion bent into cylindrical shape;

Fig. 6 is a view similar to Fig. 5, illustrating a tap as being passed through the cylindrical portion;

Fig. 7 is a view similar to Fig. 5, illustrating the binding screw as placed in the cylindrical thread-

2

ed portion and as having one head assembled thereon;

Fig. 8 is a view similar to Fig. 7 but showing in section the other head of the binding screw as mounted thereon.

In proceeding with this invention I provide a length of wire and flatten and roll one end of it into cylindrical shape and then thread this portion for the reception of the binding screw. 10 This eliminates the necessity of providing a separate part and soldering it onto the wire. The finding in this form may then be utilized as heretofore for the assembly of an ornament thereon, and the mounting of the binding screw in position.

With reference to the drawings, 10 designates a length of cylindrical wire which has been bent into U-shape providing a short leg 11 and a longer leg 12. The longer leg 12 is swedged as at 13 (see Fig. 3) so as to flatten the same and after this flattening the flattened portion 13 is annealed. A first rolling as at 14 (see Fig. 4) is provided so that this flattened portion 13 will extend partially about a cylindrical form. The next operation is swedging or rolling, which bends the flattened portion as at 15 (see Fig. 5) into cylindrical form, and thereafter the inner surface 16 of this cylindrical form is tapped as by a tap 17, as shown in Fig. 6.

30 After the finding has been formed, such as on completion of tapping as shown in Fig. 6, a binding screw 18 as shown in Fig. 7 having one head 19 previously assembled thereon is threaded into the cylindrical tapped portion 15 as shown in Fig. 7 and thereafter a larger head 20 which serves as a handle is assembled on the other end of the screw 18 as shown in Fig. 8. Any ornament such as 21 (see Fig. 1) is assembled on the short arm 11 of the ear wire so as to provide the same 40 of an ornamental appearance. The ornament will have a jaw portion 22 which will be positioned axially opposite the head 19 and the lobe of the ear may be positioned between the portions 19 and 22 and by turning the handle head 45 20 the screw 18 will be moved so as to engage the lobe of the ear and bind the ornament 21 thereon.

I claim:

1. The method of forming a finding for an ear wire comprising providing a length of plated wire cylindrical in cross section, flattening one end portion of said wire, rolling the flattened portion about an axis transverse to said wire and parallel to the flattened surface into cylindrical shape with the end at the juncture of the cylin-

drical cross section and flattened portion and threading the inner surface of said cylindrical shaped portion.

2. The method of forming a finding for an ear wire comprising providing a U-shaped length of plated wire, flattening one end portion of said wire, rolling the flattened portion about an axis transverse to said wire and parallel to the flattened surface into cylindrical shape with the end at the juncture of the cylindrical cross section and flattened portion and threading the inner surface of said cylindrical shaped portion.
